UNITED STATES PATENT OFFICE

HENRY W. ROOS, OF CINCINNATI, OHIO

APPARATUS FOR FORMING CONCRETE FLOORS

Application filed March 13, 1930. Serial No. 435,468.

This invention relates to improvements in forms for forming concrete floor molds, and especially to forms for molding beams and girders on which the floor is supported, and particularly to means for temporarily supporting such forms in the floor mold.

The principal object of the invention is to provide a simple and inexpensive support for a floor mold on which beam or girder forms may be directly supported and on which the floor forms between the beams or girders may also be supported.

Another object of the invention is to provide a temporary support or shore for floor molds adapted to rest in contact with the side of the beam and support the forms for the beam mold.

Still another object of the invention is to provide a shore of this kind having tops adapted to cooperate with the floor forms in the floor mold and provided with means adapted to engage and support the floor forms.

To these and other ends, the invention consists in the construction and arrangement of parts that will appear from the following description when read in conjunction with the accompanying drawings, the novel features being pointed out in the claims following the specification.

In the drawings:

Fig. 1 is a fragmentary plan view of a floor mold constructed according to one embodiment of the invention;

Fig. 2 is a front elevation of a shore especially constructed for supporting beam and girder forms at their intersection and showing a fragment of a beam form connected thereto;

Fig. 3 is a side elevation of the same showing a fragment of a girder form connected thereto;

Fig. 4 is a similar view showing the form supporting arm dropped to inoperative position;

Fig. 5 is a fragmentary perspective view of the inside of a girder mold looking into an intersecting beam mold;

Fig. 6 is a fragmentary horizontal section taken substantially on line 6-6 of Fig. 5;

and looking in the direction of the arrow at said line;

Fig. 7 is a horizontal section through one of the shores showing how the beam and girder forms are secured thereto;

Fig. 8 is a side elevation of a shore especially adapted to support beam and girder forms at points between intersections, parts being shown in section;

Fig. 9 is a transverse section of the same taken substantially on line 9-9 of Fig. 8, and looking in the direction of the arrow at said line;

Fig. 10 is an end elevation of a form for a beam mold shown in Fig. 1, having an adjustable bottom;

Fig. 11 is an inverted plan view of the bottom of the beam form shown in Fig. 10, one of its adjusted positions being shown in dotted lines;

Fig. 12 is a side elevation of the same;

Fig. 13 is a front elevation of a modified form of the shore shown in Fig. 8, parts of the beam form supported thereon being broken away, and

Fig. 14 is a side elevation of the same.

Referring specifically to the drawings, in which like reference numerals refer to the same parts in all the figures, 1 represents a standard floor form, cut out at its corners to fit around the tops of shores 2, 3 and 4 on which they are supported. The forms 1 are assembled on the temporary supports or shores to form a floor mold. Extending across the floor in one direction is a girder mold 5, and at substantially right angles to and intersecting the girder mold is a beam mold 6. At one side of the floor, the floor frames into an outside beam or lintel 7, which frames into the column 8 for permanent support. The girder 5 also frames into the column 8 at substantially right angles to the lintel. In the embodiment illustrated, the space between the beam and the lintel is too narrow for more than one row of the standard unit forms 1, so that the narrow opening between the unit forms and the lintel is shown filled in with a row of narrow forms 9.

Referring to Fig. 1, it will be noted that at the points of intersection between the beams

and girders, the tops 4 of the shores are of only one-quarter the area of the standard or usual top 2. The corner of but one floor form 1 fits around the top 4 and is supported 5 at that point, while four floor forms fit around the top 2 and are supported at that point. Between the intersections of the beams and girders the shore tops 3 are shown, which are of one-half the area of the tops 2, and two of 10 the floor forms 1 or 9 fit around it and are supported at that point. The special shores having the tops 3 and 4 are mounted in the sides of the beam and girder molds between the beam or girder forms, and the forms are 15 secured thereto and supported thereon.

The shore 4 having a one-quarter head is shown in detail in Figs. 2 to 7 inclusive, and comprises an upright supporting member 10 having two vertical walls 11 and 12 arranged 20 at substantially right angles to each other. Secured to or formed integral with one of said walls, the wall 11 in the embodiment illustrated, is a bracket 13 flush with the upper ends of the walls 11 and 12, which provides 25 a support for the top 4 seated thereon, and the walls 11 and 12 and flush with said walls. Intermediate its ends, the bracket 13 has a projection 14 on which an arm 15 is pivotally mounted. The arm 15 has a pair of ears 30 which engage opposite sides of the bracket and guide it in its pivoted movements. The outer end of the arm 15 has a substantially V-shaped opening in an upwardly and outwardly inclined finger 15^a.

35 Adjacent its outer end, the bracket 14 is slotted at 16 for the reception of a wedge 17 or other suitable means for retaining the arm in the operative position shown in Figs. 2, 3 and 6, in which its finger 15^a is adapted 40 to engage a bracket 18 in the corner of the floor form for supporting it. When the wedge is removed from its slot, the arm 15 is free to fall by gravity to the position shown in Fig. 4, in which it is released from the 45 form which may then be removed, leaving the slab of concrete formed thereon supported directly on the top of the shore.

Secured to the walls 11 and 12 of the shore, 50 by welding or other suitable means, at a point below the bracket 13 are elongated angular brackets 20, one of the brackets 20 being secured to each of the members 11 and 12 and flush with their outer edges. Each of the 55 brackets 20 has an inwardly projecting portion 21 arranged at substantially right angles to the wall 11 or 12 to which it is secured, and each is provided with a plurality of slots 22 arranged in vertical alinement.

60 The sides 23 of the beam and girder forms are bent outwardly at their ends to form flanges 24 at substantially right angles thereto, which are provided with vertically alined openings adapted to register with the openings 65 or slots 22 for the reception of bolts 25, whereby the beam or girder forms may be

secured directly to the shores. By this construction, the bolts 25 may be removed to free the beam forms from the shores before the concrete has completely set, leaving the sides 11 and 12 of the shores in contact with the 70 beams and girders at their intersection, which is usually their weakest point, so that the beam forms can be more quickly released for use in another floor mold. The upright member 10 may be made in various lengths, if 75 desired, to conform to beams or girders of various depths, and is shown secured to a bracket 27 adapted to be mounted on a post or other suitable support.

The shores having the half-heads 3 are 80 constructed in a manner similar to those having the quarter-heads 4 already described. Referring to Figs. 8 and 9, it will be noted that the top 3 is secured to the top of a support 26 rising vertically from a bracket 27 85 adapted to be mounted on a post or other suitable support and may be reinforced by means of walls 27^a arranged between the upright 26 and the bracket 27. A bracket 13 is secured to the support 26 flush with its upper 90 end, and has an arm 15 pivoted thereto to move from a position in which it is adapted to engage the floor forms to a disengaged position. A wedge 17 may be inserted in a slot 95 provided therefor in the bracket for maintaining the arm in operative position.

Secured to and flush with the vertical edges of the support 26 are angle brackets 20' having the parts 21' arranged at substantially right angles to the support 26, and provided with a plurality of vertically alined 100 slots 22' for cooperation with the openings in the beam or girder forms for the reception of the bolts 25, whereby the beam or girder forms are detachably mounted directly on 105 the shores.

Referring to Figs. 13 and 14, a slightly modified form of the shore shown in Figs. 8 and 9 is illustrated, which is substantially 110 the same in all respects except that the upright member 26' is provided with a plurality of vertically alined openings 50 adjacent its lateral edges or on opposite sides of the vertical plane of the bracket 13. The bottom walls 51 of the beam forms project beyond the 115 ends of the side walls to meet the bottom wall of the adjacent form at a point substantially intermediate the side edges of the supports 26' or 26. The bottom walls 51 are also provided with downwardly projecting flanges 52 120 along their sides, which may be provided with openings adjacent their ends adapted to register with one or another of the openings 50 for the reception of bolts 25 whereby the bottom walls of the beam forms may be secured directly to the shores. The sides of the beam forms are provided with a plurality of vertically alined openings 53 arranged 125 in horizontal planes, with which openings in the flanges 52 are adapted to register for the 130

reception of bolts 25, whereby the bottom wall is secured to the side walls of the beam forms. By moving the bottom wall to register with other openings 53, the bottom wall 5 may be secured to the side walls in other horizontal planes to vary the depth of the beam form. The openings 50 in the shore are arranged to lie in horizontal planes corresponding to the horizontal planes in which the 10 openings 53 are arranged so that the bottom wall may be secured to the shores in any of the planes in which it may be secured to the side walls.

The floor forms are provided with downwardly projecting marginal flanges 55, and the top edges of the side walls have angle irons 56 secured to the outer surface, flush with the upper edge, preferably by welding. The angle irons 56 serve to reinforce the side 20 wall of the beam form along its upper edge, which abuts the lower edge of the flange 55 on the floor form.

The inner wall 30 of the lintel 7 is mounted on shores 3 and the column form in a manner similar to the side walls of the beam and girder forms. The bottom wall 31 of the lintel is secured to the inner wall 30 at one edge and to the outer wall 32 at its outer edge. The outer wall of the lintel rises above the 30 inner wall a distance equal to the thickness of the concrete slab to be formed on the floor mold, and may be anchored or connected to the inner wall at frequent intervals by means of wires, as usual in the art. The bottom 35 of the lintel may be supported directly on the shores as shown. In the embodiment illustrated in the drawings, the ends of the bottoms of the lintel forms are cut out to fit around the tops 2 of the shores and provided 40 with brackets similar to the brackets 18, whereby they may be engaged with and supported on the arms 15 of the shores, the ends of said bottoms adjacent the column being mounted directly on the column form. By 45 this arrangement, the arms 15 may be disengaged from the lintel forms to permit their removal for use in other places, while leaving the concrete supported directly in contact with the tops of the shores. If desired, 50 the beam bottoms may be constructed and supported directly on the top of shores in a similar manner.

The girders are usually of greater vertical depth than the beams, with the result that 55 where they intersect, as at 35, an open space is left in the girder between and below the adjacent ends of the beam. This space is conveniently bridged or covered by means of a U-shaped piece of sheet material 36, see 60 Fig. 5, adapted to engage the sides of the girder mold beneath the ends of the beam and be supported on the bottoms of the adjacent girder forms.

Referring to Fig. 1, it will be noted that 65 the beam and girder forms are of a length

substantially equal to the length of a side of a standard floor form 1; however, when it becomes necessary to employ narrow floor forms, such as indicated at 9, a short opening is left in the beam mold. This opening is 70 filled or bridged by means of a short form 40. The beam forms 40 may be constructed like the standard forms 5 but of a length to fit the particular opening, or it can be made in two end sections to overlap at the middle, and the end sections mounted on the shores 75 in the manner described.

In Figs. 10, 11 and 12 is shown a special beam form having a longitudinally adjustable bottom wall adapted to fit in the short 80 opening. The side walls 60 of this form are cut to the length of the opening and may be provided with vertical flanges at their ends whereby they may be secured to the adjacent shores. They are also provided with the usual openings whereby the bottom wall may be secured thereto. The bottom wall is made of two parts 61 and 62, the inner end of the part 62 overlapping the inner end of the part 61, and the outer end of each part is reinforced by means of an angle iron 63 secured thereto preferably by welding and providing 85 downwardly projecting flanges at the ends.

Secured to the under surface of the part 61, preferably by welding, are the rods or bars 63^a and 64. The bar 63^a is substantially flush with one of its sides and parallel therewith, and the bar 64 is spaced inwardly from the side edge a distance substantially equal to the thickness of the bar. Similar rods or bars 63' and 64' are secured at one of their ends to the under surface of the part 62, the other or inner end being free therefrom to provide a clearance for the part 61.

The bar 63' is flush with one of the side edges of the part 62 and the bar 64' is spaced from the other side edge a distance substantially equal to the thickness of the bar. By this arrangement, the bars 63^a, 64' and 63', 64 overlap each other at their inner ends, 105 where they are provided with slots or openings adapted to register with each other in various positions of adjustment for the reception of bolts 65, whereby the parts may be secured in the adjusted position. By removing the bolts from the openings, the parts 61 and 62 may be adjusted to form a bottom wall of the desired length, and the bolts reinserted in newly registering openings for securing them in the adjusted position. The bolts 66 which secure the bottom wall to the side walls may extend through registering slots in the bars 63' and 64 and 63^a and 64' and thus cooperate with the bolts 65 for securing the parts in adjusted position. The heads of the bolts 65 are arranged between the bars 63^a and 63' and the side walls of the form. These bolts are therefore countersunk so that the side walls may lie in close contact with the side edges of the bottom wall. 115

Although only one embodiment of the invention is shown and described herein, it will be understood that this application is intended to cover such changes or modifications as come within the spirit of the invention or scope of the following claims.

I claim:

1. Apparatus for forming concrete floor molds, comprising a shore having an upright support comprising a pair of walls arranged at substantially right angles to each other, a top secured to the upper end of said support with its edges flush with said walls, and a bracket mounted on the support between said walls for supporting a floor form.
2. Apparatus for forming concrete floor molds, comprising a shore having an upright support comprising a pair of walls arranged at substantially right angles to each other, a top secured to the upper end of said support with its edges flush with said walls, and an arm pivoted between said walls for supporting a floor form.
3. Apparatus for forming concrete floor molds, comprising a shore having an upright support, a top secured to the upper end of the support flush with one side thereof, a form supporting arm pivotally mounted on the other side of said support, and a bracket for a beam form also secured to said support.
4. Apparatus for forming concrete floor molds, comprising a shore having an upright support, a top secured to the upper end of the support flush with one side thereof, a form supporting arm mounted on the other side of said support, a pair of vertically arranged brackets secured to said support, and flanges on said brackets arranged at substantially right angles thereto and adapted to support the adjacent ends of beam or girder forms.
5. Apparatus for forming concrete floor molds, comprising a shore having an upright support, a top secured to the upper end of the support flush with one side thereof, a form supporting arm mounted on the other side of said support, a pair of vertically arranged brackets secured to said support, and flanges on said brackets arranged at substantially right angles thereto and adapted to have the vertical sides of beam or girder forms secured thereto.
6. Apparatus for forming concrete floor molds comprising a shore having an upright support with a plane surface on one side thereof, a top on said support having one side arranged in the plane of said surface and projecting from said support on its opposite side, and form supporting means on said opposite side of the support movable from an inoperative position under the projecting top to an operative position projecting therefrom.
7. Apparatus for forming concrete floor molds comprising a shore having an upright

support, two vertically arranged plane side walls on said support meeting each other to form an angle between them, a top arranged over the opening between said sides and flush with said plane side walls, and a form support mounted thereon in said angle and movable to and from an operative form engaging position.

8. An apparatus for forming concrete floor molds comprising a shore having an upright support, two vertically arranged plane side walls on said support meeting each other to form an open substantially right angle between them, a bracket on one of said walls arranged in a plane substantially parallel with the other of said walls, a form support movable on said bracket to and from an operative form engaging position, and means cooperating with said bracket for securing the form support in operative position.

In witness whereof, I have hereunto signed my name.

HENRY W. ROOS.
